MOP STRUCTURE

Frank A. Trindl and Catherine O. Trindl,
Chicago, Ill.

Application September 11, 1941, Serial No. 410,352

3 Claims. (Cl. 15—244)

This invention relates to cleaning apparatus and is more particularly directed to absorbent mops having the mopping portion thereof formed of elastic cellular material.

The present application is a continuation-in-part of our co-pending application entitled "Mop and mop squeezer," U. S. Serial No. 313,352, filed January 11, 1940, now Patent Number 2,290,217, July 21, 1942.

We have found that a mop comprising a substantially rigid back and a mass of absorbent elastic cellular material is more convenient to handle and satisfactory in its operation than the old-fashioned types of mops formed of rags or cords. In particular, we have found that the recently developed synthetic material marketed under the name "cellulose sponge" has superior ability to remove moisture from a surface such as a floor and will withstand a remarkable amount of wear.

The mop construction herein disclosed is preferably shaped in a manner in which it can be conveniently used with apparatus for expressing moisture therefrom.

One of the important objects of this invention is to provide a highly satisfactory form of mop using elastic cellular material as the absorbent portion thereof.

Another object of this invention is to provide a mop construction of such shape as to cooperate with a moisture expressing device carried on the rim of a pail.

A further object of the present invention is to provide a mop construction having a compressible absorbent mopping portion which is carried by a head portion formed of material of greater rigidity than the mopping portion.

A still further object of this invention is to provide a mop construction having a compressible and slotted absorbent mopping portion whereby a large absorbent area is exposed to the surface being mopped with the slits facilitating flow of water to the absorbent portion during mopping operations and facilitating flow of water out of the absorbent portion when compressed or squeezed.

Another and still further object of this invention is to provide a mop construction having a substantially rigid back and a compressible absorbent mopping portion with a flexible hinged connection therebetween.

Still another object of the present invention is to provide a novel method for assembling a mop construction having a substantially rigid

back and a compressible absorbent mopping portion.

The novel features believed to be characteristic of the present invention are set forth with particularity in the appended claims. The invention itself, however, both as to its organization and manner of construction, together with further objects and advantages thereof, may best be understood by reference to the following description taken in connection with the accompanying drawing, in which:

Figure 1 is a plan view in elevation showing the relation between the mop construction of the present invention and a moisture-expressing device mounted on the rim of a pail;

Figure 2 is an end view of one form of a mop device constructed in accordance with the principles of the present invention;

Figure 3 is an end view illustrating the mop of this invention when seen in operation;

Figure 4 is a bottom view in elevation of the mop construction illustrated in Figures 2 and 3;

Figure 5 is an end view of a modified form of mop construction with the sponge shown in transverse, intermediate cross section;

Figure 6 is a bottom view similar to Figure 4 and illustrating the form of mop shown in Figure 5;

Figure 7 is a fragmentary view as seen when taken substantially along the off-set planes indicated by the broken line VII—VII of Figure 8 and illustrating a portion of the flexible backing between the broken absorbent portion and the substantially rigid back of the mop; and

Figure 8 is an enlarged fragmentary view in vertical section as seen when taken substantially in the plane indicated by the line VIII—VIII of Figure 1.

As best shown in Figure 1, the mop construction 10 of the present invention is adapted for use with a moisture expressing device 11. This moisture expressing device generally comprises a resilient perforated sheet metal trough 12 removably supported upon the rim 13 of a pail or bucket 14 by means of four hooks 15, 16, 17 and 18.

It will be noted that the trough 11, as viewed from the top, has the shape of an isosceles trapezoid, that is, it has two sides parallel but of unequal length with its two ends extending at equal oblique angles to the sides. One side of the trough 11, between the hooks 15 and 17, is therefore considerably shorter than the other side, between the hooks 16 and 18, which enables the trough to be suspended from the rim of

a pail 14 to one side of the center line thereof, as shown in Figure 1.

The mop construction 10 is shaped, when viewed from the top, in much the same manner as the trough 11 for the purpose of providing the greatest length possible in cooperation with and for ease in centering the mop in the moisture expressing device between the rim portions of the pail 14 from which the trough is suspended.

This construction provides a mop back having one side 19 considerably shorter than the other side 20. The end portions 21 and 22 extend away from the short side 19 at equal oblique angles. The oblique end portions are connected to the long side 20 by the end portions 23 and 24 which extend in substantially right-angular relationship to the long side of the mop back.

Various modifications may be made in the mop construction. The preferred form as illustrated in Figure 2, comprises a back or head portion 28 shaped in plan view as illustrated in Figure 1. An angularly extending opening 26 (Figure 1) is provided in the back or head portion 28 centrally of and immediately adjacent a longitudinal edge thereof for receiving one end of a handle 27. It is preferred that the handle be inserted in the substantially rigid head portion adjacent the short side 19 in order that the longest edge of the absorbent mopping portion be the most forward edge during the mopping operations. However, the handle receiving aperture may be placed adjacent the long edge 20 if desired.

In this form of construction, the absorbent mopping portion is formed of a plurality of separate sections 29, 30, 31 and 32. The absorbent portion 28 of the mop construction is preferably formed of an elastic cellular material such as a sponge. The slits 33 between the separate sections 29, 30, 31 and 32 form passages which facilitate the flow of water into the mop when it is used to pick up water from a floor and which also facilitates the flow of water out of the mop when the mop is being squeezed.

While the absorbent portion 28 is illustrated as sloping outwardly from the rigid head portion 25, it is to be understood that the sides thereof may extend in any angular relation from the head portion as desired.

It will be noted from Figure 3 that the lower ends of the separate sections 29, 30, 31 and 32 in contact with a surface to be mopped are compressed in operation with the slits 33 therebetween being opened to facilitate the flow of water into the absorbent sections. By providing separate sections in the absorbent portion 28, a greater liquid absorbing area is provided during operation of the mop.

It will be noted in Figure 4 that the bottom of the absorbent sponge portion provides an outline similar to the shape in plan view of the substantially rigid head portion 25.

Another form of mop construction is illustrated in Figures 5 and 6 in which the absorbent portion 35 of the mop secured to the head portion 25 is formed of a single piece of material but is slit in a manner differently from that illustrated in Figure 2. The absorbent portion 35 is provided with a plurality of slits 36 extending up from the bottom thereof and terminating in spaced relation from the head 25. The slits 36 function in substantially the same manner as the slits 33 in the mop construction shown in Figures 2 and 3.

If desired, the slits 36 may extend longitudi-

nally along the sponge mopping portion in a manner similar to that illustrated in Figure 4 or they may terminate in spaced relation from the ends of the sponge portion in a manner as illustrated in Figure 6. Thus, at each end of the sponge, there is left a continuous unslit portion connecting together the portions separated by the slits 36.

The sponge portions 28 and 35, illustrated in Figures 2 and 5, are each connected to the substantially rigid portion 25 in a manner as illustrated in Figures 7 and 8. As best shown in Figures 2, 3 and 5, the head portion 25 is provided with spaced longitudinally extending slots 37 and 38. These slots are preferably formed parallel to the longitudinal sides 19 and 20 and are spaced inwardly therefrom. It will be obvious, of course, from the following description that the slots may have various spaced arrangements relative to each other and to the adjacent edges of the head portion. Likewise, the slots may be formed transversely of the head portion.

The slotted face of the head portion 25 is covered by any suitable flexible backing material 39 such as fabric, rubber or the like. The rod member 40 of any flexible material such as metal, wood or the like, is inserted into each of the slots 37 and 38 to hold the inlaid backing material 39 therein. As shown in Figure 8, a staple 41 is then forced into the head portion 25 in a position bridging the slot for the purpose of retaining the backing material and rod member in place. It is to be noted that the slot 37 is of sufficient depth to include the inlaid portion of the backing material and the rod with the outer edge of the rod lying in flush relation with the outer surface of the backing material. This relation of elements is also provided in slot 38. While it is preferred that a staple 41 be used, it is to be understood that any similar suitable fastening means such as nails, tacks or the like may also be used. As shown in Figure 7, the staples 41 are spaced longitudinally along the rods 40 in each of the slots 37 and 38.

The upper surface of either of the sponge portions 28 or 35, depending on which is to be connected to the head portion 25, is covered with a layer of cementitious material 42 and the sponge portion is then applied to the fabric covered face on the head portion for connection thereto as the cementitious material dries. Obviously, the cementitious material used must be flexible after it has hardened and must be waterproof and unaffected by hot or cold liquids as either may be used in mopping surfaces.

It is to be noted in Figure 7 that the rods 40 terminate in spaced relation from the ends of the mop construction. As the sponge portion is connected to the head portion 25 only along the rods 40, which are spaced from all of the edges of the head portion, the connections act as hinges between the sponge portion and the head portion. These connections permit a limited hinging action along the sides and ends of the sponge portion relative to the head portion as shown in Figure 3 of the drawing. Consequently, the sponge portion is not apt to tear away from the back or head portion of the mop when subjected to heavy pressure and the life span of the mop is thereby increased.

While the head portion 25 is described as being substantially rigid, it being preferably formed of wood or a plastic material, it is to be understood that a head portion formed of any semi-

rigid material such as dense rubber or like material having similar characteristics may be used equally as well. Furthermore, the angularity of the handle 27 with respect to the head portion 25 may be varied depending upon the angle at which the mop may be most conveniently used.

While particular embodiments of this invention have been illustrated, it will, of course, be understood that the invention should not be limited thereto, as many modifications may be made and, therefore, it is contemplated by the appended claims to cover all such modifications as fall within the true spirit and scope of the present invention.

We claim as our invention:

1. A mop construction comprising an elongate head portion having longitudinal slots in a face thereof, said slots being spaced from each other and from the longitudinal edges of said head portion, a flexible backing member seated on said face and in said slots, a flexible rod member seated on said backing member in each of said slots, said rod members terminating short of the ends of said head portion, means spaced longitudinally along each of said rod members for holding them and said backing member on said head portion, and a compressible absorbing mopping portion carried by said backing member for limited hinging action around and on the ends of said rod members, said flexible backing and said mopping portion being of such a size as to be disposed within the confines of the edges of the side of the head portion to which they are secured.

2. A mop construction comprising an elongate head portion having longitudinal slots in a face thereof, said slots being spaced from each other and from the longitudinal edges of said head portion, said head portion being adapted for receiv-

ing a handle member for operating said mop, a fabric backing strip seated on said face and in said slots, a flexible rod seated on said backing strip in each of said slots, said rods terminating short of the ends of said head portion, staple members embedded in said head portion and being spaced longitudinally along each of said rod members in straddling relation thereto for holding said rods and backing strip on said head portion, a sponge mopping portion, and means for connecting said sponge portion to said fabric strip whereby said sponge portion is mounted for limited hinging action around and on the ends of said rod members.

3. A mop construction adapted for use with a moisture-expressing device of conforming configuration, comprising an elongate head portion having opposed longitudinal sides one of which is shorter than the other and slots in a face thereof parallel with said longitudinal sides and spaced from each other and from said longitudinal sides, a fabric backing strip seated on said face and in said slots, a flexible rod seated on said backing strip in each of said slots, said rods terminating in spaced relation from the ends of said head portion, staple members embedded in said head portion and being spaced longitudinally along each of said rod members in straddling relation thereto for holding said rods and said backing strip on said head portion, a sponge mopping portion divided into a plurality of sections by slits extending upwardly from the under surface thereof, and liquid resistant cementing means connecting said mopping portion to said backing strip whereby said mopping portion is mounted for limited hinging action around and on the ends of said rod members.
